COMPRESSOR UNLOADER

William P. Caine, Birmingham, Ala.

Application February 4, 1946, Serial No. 645,382

9 Claims. (Cl. 230—24)

2

This invention relates to an unloading device for an elastic fluid compressor and has for an object to provide a device of the character designated which shall be adapted for use with a compressor driven at constant speed, and shall include means for by-passing excess fluid to the intake side of the compressor.

A further object of my invention is to provide a compressor unloader including means for positive closing of communication between the unloader and the low pressure intake of the compressor when the compressor is shut down.

A more specific object of my invention is to provide a compressor unloader including a differential piston for controlling the back flow of excess fluid to the intake of the compressor, together with variable means to control the actuating fluid for the piston.

Briefly, my invention comprises a differential piston in which both the larger and the smaller piston elements each comprises a valve, the smaller valve controlling the back flow of excess fluid to the intake of the compressor when it is in operation, and the larger being adapted to close the back flow of air from the receiver to the compressor when the compressor is shut down. The action of the differential piston is controlled by a spring biased valve operated responsive to receiver pressure, whereby when the receiver pressure reaches a predetermined value, the differential piston is actuated. The piston is further controlled by a constant leakage device, the amount of leakage through said device being adjustable, whereby the sensitiveness of control may be varied. When the compressor is not in operation, and with pressure in the receiver, means are provided to operate the differential piston to close off communication between the receiver and the compressor and to close the constant leakage device. By means of my improved mechanism, I have provided a very sturdy, yet delicately adjustable unloading device which provides positive and sensitive control of the fluid flowing to the receiver and the excess fluid back to the compressor.

Apparatus embodying features of my invention is illustrated in the accompanying drawings, forming a part of this application, in which

Fig. 1 is an assembly view showing my improved device in association with a compressor including high and low pressure cylinders;

Fig. 2 is a detail sectional view of the unloading valve; and

Fig. 3 is a wiring diagram illustrating the con-

nections to a solenoid operated valve employed with my invention.

Referring now to the drawing for a better understanding of my invention, I show in Fig. 1 a compressor including a low pressure cylinder 10, and a high pressure cylinder 11, both being driven by a suitable motor M. Fluid being compressed is admitted to the low pressure cylinder 10 from an intake conduit 12 which may be provided with the usual filter 13. Fluid is discharged from the low pressure cylinder 10 through a discharge conduit 14, intercooler 16, and conduit 17 to the high pressure cylinder 11. Fluid is discharged from the high pressure cylinder 11 through a conduit 18 and my improved unloading device, indicated generally by the numeral 19, and thence through a conduit 21 to a receiver 22. In normal operation, excess fluid is discharged from the unloading device 19 through a conduit 20 which connects to the intake conduit 12 of the low pressure cylinder 10.

My improved unloader valve embodies a housing connected to the compressor discharge conduit 18 through a passage 24, to the intake conduit 23 through a passage 26, and to the conduit leading to the receiver at 27. Within the housing of the unloader valve is a cylindrical chamber 28. A transverse division wall 29 extends across the housing and is provided with an opening 30 having a valve seat 31 on the upper side thereof. Below the opening 30 and in line therewith, is an opening 32 leading to the passage 26 and provided with a valve seat 33 on the lower side thereof. Slidably mounted within the cylindrical chamber 28 is the larger end 34 of a differential piston which is mounted on a stem 35 extending down through the opening 32. The smaller end 36 of the differential piston is mounted on the lower end of the stem 35 within the passage 26 leading to the intake conduit 23. The larger end 34 of the differential piston forms a valve which seats on the valve seat 31 when the piston is in its lowermost position. The smaller end 36 forms a valve which seats on the valve seat 33 when the differential piston is in its uppermost position as shown in the drawing. It will be seen that when the differential piston is in its uppermost position, communication between the compressor connection 24 and 26 is closed off by the smaller end 36 of the piston, whereas when the piston is in any position below that shown in the drawing, fluid may flow from the passage 24 past the end 36 into the intake connection passage 26.

Mounted over the valve housing just described is an operating valve 40 defining a chamber 37

connected through a passage 38 to a pilot valve chamber 39. Within the chamber 37 is a valve 41 controlling a passage 42 leading to the cylindrical chamber 28 in which the differential piston 34 is mounted. The valve 41 is biased toward an open position by means of a spring 43. Mounted over the valve 41 is a diaphragm 44 forming the upper wall of the chamber 37 and carrying a stem 46 which bears downwardly on the valve 41 to hold it closed until a predetermined pressure is reached in the receiver. A spring 47 bears against the opposite side of the diaphragm 44 and is adjustable by means of an adjusting screw 48 extending through a spring housing 49. The opening of the valve 41 is thus responsive to a predetermined receiver pressure.

Within the housing 40 is a passage 51 communicating with the pilot valve chamber 39, and which has connected thereto a conduit 53 leading to the compressor intake connection 26. A conduit 56 connects the pilot valve chamber 39, opposite the passage 38, to the receiver connection 27.

Slidably fitting within the pilot valve chamber 39 is a pilot valve 57 of the piston type having enlarged ends 58 and 59 which, when the valve is in the position shown in Fig. 2 span the passage 38. Also, in that position, the lower, enlarged end 59 separates the passages 51 and 38. The valve 57 is provided with a stem 60, which is connected at its upper end to a solenoid 61. When the compressor is in operation, the valve 57 assumes the position shown in Fig. 2 of the drawing and is held in that position by means of the solenoid 61, which is energized in a manner to be described later, thus to hold the valve 57 in its uppermost position. When the compressor is not in operation, the solenoid 61 is de-energized and a spring 62 causes the valve 57 to move to its lowermost position. In its lowermost position, a valve 63 on the lower end thereof, covers a port 64 leading to the conduit 53 and thus closes off communication between the chamber 28 and the intake connection 26. The amount of opening of the port 64 is controlled by means of a plug valve 66 screwed into the lower end of the housing.

In Fig. 3 of the drawing, I show diagrammatically one way of operating the solenoid 61. The motor M is shown provided with a field 67 and the solenoid 61 is in circuit with the field whereby, when the motor in operation reaches full speed the solenoid is energized.

The operation of my improved unloading apparatus is as follows: With the compressor in operation and with fluid under pressure being discharged through the conduit 18 to the unloading device through the connection 24, pressure acting on the larger end 34 of the differential piston holds it in the upper position shown in Fig. 2 of the drawing with the lower end 36 seated on the valve seat 33. Fluid being compressed thus flows from the connection 24 through the opening 30 and out through the connection 27 to the receiver. Receiver pressure passes from the connection 27 through the conduit 56, around the valve 57 into the passage 38 leading to the control valve chamber 37. When the pressure within the receiver reaches a predetermined amount, it raises the diaphragm 44 and stem 46, permitting the spring 43 to open the valve 41. This permits receiver pressure to flow past the valve 41 into the chamber 28 above the larger end 34 of the differential piston. As the pressure on opposite sides of the larger end

34 of the differential piston approaches equilibrium, the piston moves downwardly, thus moving the valve 36 off its seat 33, thus connecting the inlet connection 24 with the connection 26 leading to the compressor intake conduit 23. At the same time, pressure from the chamber 28 flows through the passage 51 to the pilot valve chamber 39 and thence through the port 64 to the conduit 53 and the intake connection 26. So long as the compressor is delivering more fluid than is required to maintain the receiver 22 at its predetermined pressure, the action just described will continue and the smaller end 36 of the differential piston will stay off its seat thus allowing a part of the fluid delivered by the compressor to by-pass through the connection 26 and intake conduit 23. Should the pressure within the receiver fall below the predetermined amount, the spring 47 moves the diaphragm 44 and stem 46 downwardly to close the valve 41. Fluid under pressure above the larger end 34 of the differential piston is then exhausted through passage 38, port 64 and conduit 53 and the differential piston moves upwardly so that the smaller end 36 is again seated on its seat 33.

When the compressor is shut down, the solenoid 61 is de-energized and the spring 62 moves the pilot valve 57 to its lowest position. In this position, the valve 63 covers the port 64 thus closing off communication between the chamber 28 and the intake connection 26. With the pilot valve 57 in its lowest position, receiver pressure from the connection 27 and conduit 56 flows into the chamber 28 through the passage 51 and around the pilot valve 57, thus causing the differential piston to move to its lowest position with the larger end 34 seated on the valve seat 31, thus closing off communication between the receiver and the intake connection 24.

When starting up the compressor after a shut down, the differential piston will be in its lowermost position, with the larger end 34 seated on the seat 31. Until the motor is up to speed, the solenoid 61 will be de-energized and the valve 57 in its lowermost position. Fluid delivered by the compressor through the connection 24 will thus by-pass through the passage 32 to the intake connection 26. As soon as the motor is up to speed, the solenoid 61 is again energized and the pilot valve 57 is moved to its uppermost position as seen in Fig. 2 of the drawing.

From the foregoing, it will be apparent that I have devised an improved compressor unloader which is simple and sturdy of design, reliable in operation, and sensitive in its control.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are specifically set forth in the appended claims.

What I claim is:

1. In apparatus of the character described including a fluid compressor having an intake conduit and a discharge conduit, the latter delivering compressed fluid into a receiver, an unloader interposed in the discharge conduit between the compressor and the receiver and comprising a housing communicating with the compressor and the receiver, and a conduit connecting the housing with the compressor intake, a differential piston and cylinder therefor disposed within the housing and normally subject to receiver pres-

sure between its ends, a valve controlling communication between the housing and the compressor intake carried by the smaller end of the differential piston, a valve operable responsive to receiver pressure for admitting fluid from the receiver into the cylinder at the outer, larger end of the differential piston, a conduit affording communication between the receiver and the cylinder at the larger, outer end of the differential piston and a second valve in said conduit for controlling said communication, a valve forming a part of the larger end of the differential piston and disposed, when the piston is moved responsive to fluid pressure admitted to the cylinder through said by-pass conduit to close off communication through the housing between the receiver and the intake to the compressor.

2. In apparatus of the character described including a fluid compressor having an intake conduit and a discharge conduit, the latter delivering compressed fluid into a receiver, an unloader interposed in the discharge conduit between the compressor and the receiver and comprising a housing communicating with the compressor and the receiver, and a conduit connecting the housing with the compressor intake, a differential piston and cylinder therefor disposed within the housing and normally subject to receiver pressure between its ends, a valve controlling communication between the housing and the compressor intake carried by the smaller end of the differential piston, a valve operable responsive to receiver pressure for admitting fluid from the receiver into the cylinder at the outer, larger end of the differential piston, a by-pass conduit affording communication between the receiver and the cylinder at the larger, outer end of the differential piston and a second valve in said conduit for controlling said communication, a valve forming a part of the larger end of the differential piston and disposed when the piston is moved responsive to fluid pressure admitted to the cylinder through said by-pass conduit, to close off communication through the housing between the receiver and the intake to the compressor, a second conduit affording communication between the cylinder and the compressor intake through said hollow stem, a valve for closing said communication, and means operable upon closing off communication through the housing by the differential piston to close said last mentioned valve.

3. In apparatus of the character described including a fluid compressor having an intake conduit and a discharge conduit, the latter delivering compressed fluid into a receiver, an unloader interposed in the discharge conduit between the compressor and the receiver and comprising a housing communicating with the compressor and the receiver and a conduit connecting the housing with the compressor intake, a differential piston and cylinder therefor disposed within the housing and normally subject to receiver pressure between its ends, a valve controlling communication between the housing and the compressor intake carried by the smaller end of the differential piston, a second valve operable responsive to receiver pressure for admitting fluid from the receiver into the cylinder at the outer, larger end of the differential piston, and means to adjust said second valve to open at a predetermined receiver pressure.

4. In apparatus of the character described including a fluid compressor having an intake con-

duit and a discharge conduit, the latter delivering compressed fluid into a receiver, an unloader interposed in the discharge conduit between the compressor and the receiver and comprising a housing communicating with the compressor and the receiver and a conduit connecting the housing with the compressor intake, a differential piston and cylinder therefor disposed within the housing and normally subject to receiver pressure between its ends, a valve controlling communication between the housing and the compressor intake carried by the smaller end of the differential piston, a second valve operable responsive to receiver pressure for admitting fluid from the receiver into the cylinder at the outer, larger end of the differential piston, a second housing joined to the first mentioned housing and having passages therein communicating with the receiver and said second valve, and with the cylinder at the outer end of the differential piston and the compressor intake, a pilot valve controlling said passages, an electric motor for driving the compressor, and a solenoid in circuit with the motor field for controlling the position of the pilot valve.

5. In apparatus of the character described including a fluid compressor having an intake conduit and a discharge conduit, the latter delivering compressed fluid into a receiver, an unloader interposed in the discharge conduit between the compressor and the receiver and comprising a housing communicating with the compressor and the receiver and a conduit connecting the housing with the compressor intake, a differential piston and cylinder therefor disposed within the housing and normally subject to receiver pressure between its ends, a valve controlling communication between the housing and the compressor intake carried by the smaller end of the differential piston, a second valve operable responsive to receiver pressure for admitting fluid from the receiver into the cylinder at the outer, larger end of the differential piston, a second housing joined to the first mentioned housing and having passages therein communicating with the receiver and said second valve and with the cylinder at the outer end of the differential piston and the compressor intake, a pilot valve having an end portion disposed when the valve is in one extreme position to separate the two passages and when in the other extreme position to span the two passages and close off communication with the compressor intake, and means responsive to operation of the compressor to move the valve to the first mentioned extreme position.

6. In apparatus of the character described including a fluid compressor having an intake conduit and a discharge conduit, the latter delivering compressed fluid into a receiver, an unloader interposed in the discharge conduit between the compressor and the receiver and comprising a housing communicating with the compressor, there being a conduit in the housing communicating with the compressor intake and discharge conduits and the receiver, a differential piston and cylinder therefor disposed within the housing and normally subject to receiver pressure between its ends, a valve controlling communication between the compressor discharge and intake conduits carried by the smaller end of the differential piston, a second valve controlling communication between the receiver and the compressor discharge on the larger end of the differential piston, and other valve means operable responsive to receiver pressure for ad-

mitting fluid from the receiver into the cylinder at the outer, larger end of the differential piston.

7. In apparatus of the character described including a fluid compressor having an intake conduit and a discharge conduit, the latter delivering compressed fluid into a receiver, an unloader interposed in the discharge conduit between the compressor and the receiver and comprising a housing communicating with the compressor, there being a conduit in the housing communicating with the compressor intake and discharge conduits and the receiver, a differential piston and cylinder therefor disposed within the housing and normally positioned to pass fluid delivered by the compressor to the receiver, a valve controlling communication between the compressor discharge and intake conduits carried by the smaller end of the differential piston, a second valve operable responsive to receiver pressure for admitting fluid from the receiver into the cylinder at the outer, larger end of the differential piston, a third valve carried by the larger end of the differential piston for controlling communication between the compressor discharge conduit and the receiver, and a conduit having a restricted opening therein connecting the cylinder with the conduit leading to the compressor intake.

8. In apparatus of the character described including a fluid compressor having intake and discharge conduits, the latter delivering compressed fluid into a receiver, an unloader interposed between the compressor discharge and intake conduits and comprising a housing, there being a passage in the housing communicating

directly with the receiver and with the compressor intake and discharge conduits, a pressure responsive double acting valve disposed when in normal position to close off the compressor intake conduit from the discharge conduit and when in unloading position close off the passage from both said intake and discharge conduits, and pressure means to move the valve to unloading position when pressure in the receiver reaches a predetermined value.

9. In apparatus of the character described including a fluid compressor having intake and discharge conduits and a receiver, an unloader embodying a housing to which fluid under pressure is delivered through the discharge conduit, a conduit connecting the intake conduit with said unloader, a conduit connecting the housing to the receiver, a valve in the housing adapted when open to connect the intake and discharge conduits, a differential piston for opening said valve, and pressure regulating means to admit fluid under pressure from the receiver to said piston when pressure in the receiver reaches a predetermined value.
